[57] ABSTRACT

Novel quaternary ammonium compounds which include the adamantane ring system linked to the quaternary ammonium group by a hydrocarbon chain or by other functional groups, such as ether, carboxylic ester, carboxamide, keto, carbamate ester, thiocarbamate ester, etc.

4 Claims, No Drawings

**NEW QUATERNARY COMPOUNDS HAVING
ANTI-MICROBIAL ACTIVITY**

This is a continuation, of application Ser. No. 39,536 filed May 21, 1970 now abandoned.

The present invention relates to novel quaternary ammonium compounds represented by the general formula:

wherein R is 1-adamantyl ($C_{10}H_{15}$), R^1 is a long chain alkyl group of 10 - 18 carbon atoms, Z is selected from the group consisting of $[CH_2, O, S, C=O, COO, CONH, CHOH, NHCOO, and NHCSO]$, n is an integer from 1 to 3 and X is a compatible anion. These quaternary compounds possess superior antimicrobial, anti-caries and anti-calculus activity.

The adamantyl radical is derived from tricyclo[3.3.1.1^{3,7}] decane showing four trans cyclohexane rings as follows:

R	Z	R^1	n	Minimum Inhibitory Concentration ($\mu g/ml$)							
				S.aureus	S.mitis	B.subtilis	C.acnes	C.albicans	T.mentagrophytes	A.niger	E. coli
Adamantyl	COO	$C_{10}H_{21}$	2	1.56	6.25	1.56	1.56	12.5	7.8	31.2	25
Adamantyl	COO	$C_{12}H_{25}$	2	.02	.19	.19	6.25	.78	6.25	50	12.5
Adamantyl	COO	$C_{14}H_{29}$	2	.78	.78	.1	25	6.25	25	50	50
Adamantyl	CONH	$C_{12}H_{25}$	3	.78	.39	—	—	6.25	12.5	25	50
Adamantyl	CONH	$C_{14}H_{29}$	3	.39	.39	—	—	6.25	25	50	25
Adamantyl	O	$C_{12}H_{25}$	2	.39	.19	—	—	1.56	3.12	50	12.5
Adamantyl	O	$C_{14}H_{29}$	2	.78	.39	—	—	1.56	6.25	50	12.5
Adamantyl	NHCSO	$C_{12}H_{25}$	2	1.56	.78	.39	12.5	6.25	3.9	62.5	25

Typical examples of the quaternary ammonium compounds which may be used in this invention are:

- 2-(1'-adamantanecarbonyloxy)ethyldimethyldecyldiammoniumbromide,
- 2-(1'-adamantanecarbonyloxy)ethyldimethyltetradecylammonium bromide,
- 3-(1'-adamantanecarboxamido)propyldimethyltetradecylammonium bromide,
- 3-(1'-adamantanecarboxamido)propyldimethyltetradecylammonium bromide,
- 1-adamantyloxyethyltetradecylammonium bromide
- 1-adamantyloxyethyltetradecylammonium bromide
- 1-adamantylcarboxylmethyldimethyltetradecylammonium bromide
- 1-adamantylcarboxylmethyldimethyldecyldiammonium bromide

2-(1'-adamantylthiocarbamyloxy)ethyldimethyl-dodecylammonium bromide.

The halides such as the chlorides, fluorides and analogous compounds may also be employed herein as effective anti-bactericides.

It has been observed that the compounds generally described by the foregoing formula are particularly effective against gram positive organisms such as *Staphylococcus aureus*, *Streptococcus mitis*, *Bacillus subtilis*, *Corynebacterium acnes*, and against fungi, such as *Candida albicans*, *Trichophyton mentagrophytes* and *Aspergillus niger*, and moderately effective against *Escherichia coli* which is a gram negative bacteria. Compounds wherein R^1 is a benzyl radical in lieu of instant higher alkyl radical are devoid of antibacterial activity.

The anti-microbial nature of the instant novel compounds was shown by a standard test tube serial dilution test in which an appropriate number of test tubes of broth containing decreasing concentrations of the test agent was inoculated with the test organism. After a suitable period of incubation the tubes were examined for the presence or absence of growth. The activity of the test agent was the lowest concentration which inhibited the growth of the organism and is expressed as the minimal inhibitory concentration in $\mu g/ml$.

TABLE I

These dilution tests evidence the effectiveness of compounds of the invention against bacteria and fungi.

When used against bacteria or fungi, compounds of the instant invention may be applied directly to the surface to be protected or may be dissolved in a pharmaceutical carrier. Typically, an effective amount, e.g. 0.1 to about 10% by weight of the compound, is included in an inert carrier and a dispersing or surface active agent. Alternatively, an effective amount, e.g. 0.1 to about 10% by weight may be incorporated into a solid carrier which may be inert, such as talc, clay, diatomaceous earth, flour, etc.

The quaternary ammonium amides of adamantyl carboxylic acid are particularly effective in inhibiting the development of dental calculus as shown by the results of tests on litter-mated albino rats, in groups of 15 males and 15 females who were fed a Zipkin-McClure calculus producing diet. For 6 weeks the teeth of each animal were swabbed for 30 seconds each day with a test solution or water for the control group. The animals were then sacrificed, defleshed and scored by Baer's method for calculus. The results were analyzed by Student's *t* test and in the results quoted were 99% significant.

65	Compound	Concentration Test Solution	Calculus Reduction %	
			Males	Females
	3-(1'-adamantanecarboxamido)propyl tetradecyl dimethyl ammonium bromide	.1%	43.43	6.27

The results set forth above indicate the significant effectiveness of the quaternary compounds of the invention in inhibiting formation of oral calculus in concentrations as low as 0.1%.

When compounds of the instant invention are intended for use in compositions which reduce formation of caries and inhibit formation of oral calculus, they are typically incorporated in oral preparation in effective amounts up to about 5% by weight, preferably 0.1-1% and most preferably 0.25-0.5% by weight of the oral preparation. Typically, the oral preparation is a dentrifrice, such as a dental cream, tablet or powder, containing as a vehicle about 20-95% by weight of a water-insoluble polishing material, preferably including water-insoluble phosphate such as dicalcium phosphate, tricalcium phosphate, trimagnesium phosphate. The dentrifrice may also include water; binders such as glycerine, sorbitol, propylene glycol, and polyethylene glycol 400; detergents; gelling agents such as Irish moss and sodium carboxymethyl cellulose; additional antibacterial agents; coloring or whitening agents; preservatives; silicones; chlorophyll compounds; additional ammoniated materials; flavoring or sweetening materials; and compounds which provide fluorine-containing ion such as sodium fluoride, stannous fluoride and sodium monofluorophosphate.

The oral preparation may also be a liquid such as mouth rinse which typically contains 20-99% by weight of an aqueous alcohol such as ethanol, n-propyl, or isopropyl alcohol and being present in amount of about 5-30% by weight of the oral preparation.

Such oral preparations are typically applied by brushing the teeth or rinsing the oral cavity for 30-90 seconds at least once daily. Typical oral preparations of

the invention which can be applied in this manner are set forth below.

EXAMPLE I
Dental-Cream

	%
Quaternary ammonium ester of adamantyl carboxylic acid	0.50
Nonionic detergent*	1.00
Glycerine	22.00
Sodium pyrophosphate	0.25
Carboxymethyl cellulose	0.85
Sodium saccharin	0.20
Sodium benzoate	0.50
Calcium carbonate (precipitated)	5.00
Dicalcium phosphate dihydrate	46.75
Flavor	0.80
Water	22.15

*Tween 80 - Polyoxyethylene 920 moles ethylene oxide) sorbitan monooleate.

EXAMPLE 2
Mouthwash

	%
Quaternary ammonium amide of adamantyl carboxylic acid	0.25
Nonionic detergent (Pluronic F-68)*	1.00
Ethyl alcohol (containing flavor)	15.00
Glycerine	10.00
Saccharin	0.02
Water	73.73

*Block polymer of 80% polyoxyethylene and 20% polyoxypropylene.

The quaternary ammonium esters of adamantane carboxylic acid can be prepared by a two-step process of reacting adamantane carboxylic acid chloride with a dimethylaminoethanol to form the carboxylate, followed by quaternizing with an alkyl halide as illustrated by the following equations:

40

+ HCl

+ $\text{C}_{12}\text{H}_{25}\text{Br}$

5

EXAMPLE 3

Preparation of
2-(1'-adamantanecarboxyloxy)ethylidemethyl-dodecylammonium bromide:

A solution of 21.7g (0.11 mole) 1-adamantanecarboxylic acid chloride in 100 ml. ether was added to a solution of 19.4g. (0.22 mole) 2-dimethylaminoethanol in 200 ml. ether. The reaction mixture was stirred overnight at room temperature. Since unreacted acid chloride could still be detected by infrared spectrum, additional 15g. (0.17 mole) 2-dimethylaminoethanol was added and the reaction mixture again stirred overnight. The reaction mixture was poured into 300 ml. water and treated with 20 ml. of 10% NaOH solution. From the ether layer was recovered 23g. of oil with an infrared spectrum compatible with the proposed structure

+ Br -

The quaternary ammonium amides of adamantane carboxylic acid can also be prepared by a two-step method of reacting the adamantane carboxylic acid chloride with a dimethyl diamine and subsequently quaternizing with an alkyl halide.

Similarly, the quaternary ammonium compounds of this invention, represented by the following formulae:

wherein R, R', n and X have the same designations as in the general formula, can also be prepared by a similar two-step method of reacting a compound containing the adamantane radical with a compound containing the dimethyl amine radical and then quaternizing with a higher aliphatic halide.

The following examples illustrate the manner in which compounds of this invention are prepared.

50 of 2-Dimethylaminoethyl 1-adamantanecarboxylate.
Analysis: Calculated for $\text{C}_{15}\text{H}_{25}\text{NO}_2$: C, 71.67; H, 10.02. Found: C, 71.26, H, 9.94.

55 Ten grams (0.04 mole) of the product of step 1 was mixed with 10g. (0.04 mole) 1-bromododecane and allowed to stand for 6 weeks. The resultant crystalline mass was washed with ether and dried to 17.5g. white crystals (88% of theory). Two recrystallizations from ethyl acetate gave 15.6g. white crystals having a melting point of 176°-178°C.

Analysis:	Found	Calculated
Carbon	64.95	64.78
Hydrogen	10.15	10.07

EXAMPLE 4

The decyl homolog of the above carboxylate, i.e., where R' is $\text{C}_{10}\text{H}_{21}$, was prepared similarly to Example

3. The recovered crystals had a melting point of 183°-184.5°C and the following analysis:

	Found	Calculated	5
Carbon	63.00	63.54	
Hydrogen	9.90	9.81	

EXAMPLE 5

The tetradecyl homolog was prepared in accordance with the process defined in Example 3, yielding crystals having a melting point of 176°-178°C with the following analysis:

	Found	Calculated	20
Carbon	65.33	65.89	
Hydrogen	10.18	10.30	

EXAMPLE 6

Preparation of 3-(1'-adamantanecarboxamido)-propyldodecyldimethylammonium bromide: 2.5 grams of N,N-dimethyl-1,3-propane diamine was added to a cold solution of 5 grams 1-adamantane carboxylic acid chloride in 15cc benzene. An immediate precipitate formed. The mixture was stirred and permitted to sit for 30 minutes. The precipitate was washed with benzene several times, centrifuged, and dried in vacuum, yielding 5 grams of N-(3-dimethylaminopropyl) adamantane 1-carboxamide hydrochloride having a melting point of 154°-157°C. This product was dissolved in 150cc acetone, placed in a refrigerator for crystal growth and 4.8 gms of the product was recovered.

This hydrochloride was dissolved in 100cc water and 25cc of 1N NaOH was added. A white precipitate formed which was extracted with ether, dried by flash evaporation and 3.2 grams of the free base having a melting point of 78°-80°C was recovered. The infrared spectrum confirmed the structure of this product.

The aforedefined reaction product was quaternized by reacting 1.6 grams (0.06 mole) of N-(3-dimethylaminopropyl)-1-adamantanecarboxamide with 1.5 grams (0.06 mole) of 1-bromododecane dissolved in 4cc acetone. After standing for 2 weeks the reaction mixture was chilled with dry ice. The resultant crystalline mass was washed with ether, dried in vacuum and recrystallized from ethyl acetate, giving a crystalline product having a melting point of 122°-124°C and the following analysis:

	Found	Calculated	55
Carbon	64.81	65.47	
Hydrogen	10.84	10.40	
Molecular weight: 513.66			

EXAMPLE 7

The tetradecyl homolog of the above carboxamide was prepared in accordance with the process of Example 6. The recovered crystals had a melting point of 120°-122°C and the following analysis:

	Found	Calculated
Carbon	65.80	66.52
Hydrogen	10.54	10.61
Molecular weight 541.71		

EXAMPLE 8

Preparation of 1-adamantyloxyethyldimethyltetradecylammonium bromide:

A mixture of 3.6g (0.015 mole) 1-(2'-dimethylaminoethoxy) adamantane [prepared by the method of Charkrabarti, Faulis and Szinai, Tetrahedron Letters, No. 60, 6249 (1968)] and 4.3g (0.05 mole) 1-bromotetradecane was prepared and allowed to stand at room temperature for 6 days. The resultant solid was recrystallized from 30cc ethyl acetate to 4.75g white crystals. After recrystallization it melted at 132°-135°.

	Found	Calculated
Carbon	67.32	67.17
Hydrogen	10.96	10.87
Bromine	15.92	15.96

EXAMPLE 9

The dodecyl homolog was prepared by the procedure of Example 8, yielding hygroscopic crystals having a melting point when dry of 128°-130° and the following analysis:

	Found	Calculated
Bromine	16.91	16.91

EXAMPLE 10

Preparation of 1-adamantylcarbonylmethyldimethyltetradecylammonium bromide.

A mixture of 1.3g. (0.005 mole) 1-adamantyl bromomethyl ketone and 1.23g (0.005 mole) dimethyltetradecylamine was solubilized by the addition of 30cc acetone. The next day the solidified mixture was washed with ether and recrystallized from ethyl acetate to yield 2.1g white crystals, m.p. 134°-135.5°.

	Found	Calculated
Carbon	67.72	67.45
Hydrogen	10.65	10.51

EXAMPLE 11

The dodecyl homolog was prepared by the procedure of Example 10 yielding white crystals of melting point 140°-141.5° and with the following analysis.

	Found	Calculated
Carbon	66.55	66.36
Hydrogen	9.87	10.28

EXAMPLE 12

2-(1'-adamantylthiocarbamyl)ethyldimethyl-dodecylammonium bromide was prepared by a two-step process. First, 1-adamantyl isothiocyanate was reacted with the sodium derivative of 2-dimethylaminoethanol. The product after recrystallization from ethylacetate and from hexane had a melting point of 86°-88.5° and an analysis of

	Found	Calculated
Carbon	64.02	63.79
Hydrogen	9.41	9.28

A solution of 4.5g of the above-prepared O-(2-dimethylaminoethyl) 1-adamantylthiocarbamate and 4.0g 1-bromododecane in 15cc acetone was allowed to stand for 4 days. The product was recrystallized from ethylacetate and from acetone in white crystals, m.p. 143°-143.5° and had the following analysis

5

20

25

	Found	Calculated
Carbon	61.04	60.99
Hydrogen	9.65	9.67

Although this invention has been described with reference to specific examples, it will be apparent to one skilled in the art that various modifications may be made thereto which fall within its scope.

What is claimed is:

1. A chemical compound having the structural formula

wherein R is 1—adamantyl, R' is a long chain alkyl group of 10 to 18 carbon atoms, n is an integer from 1 to 3 and X is a compatible halide.

2. A chemical compound as set forth in claim 1, wherein n is two.

3. A chemical compound as set forth in claim 2, having the formula 2-(1'-adamantanecarbonyloxy) ethyldimethyl-dodecylammonium bromide.

4. A chemical compound as set forth in claim 2, having the formula 2-(1'-adamantanecarbonyloxy) ethyldimethyltetradecylammonium bromide.
